LIFTING MECHANISM

Dave F. Gebhart, Auburn, Calif.

Application February 16, 1956, Serial No. 565,832

6 Claims. (Cl. 294—109)

This invention relates to a lifting mechanism for lifting articles and means to release the article-supporting members from lifting engagement therewith. More particularly, in the embodiment described herein, the invention is shown accompanying a tonglike structure for hooking into one or more bales of hay, cotton, and the like.

In agriculture and industry it is frequently necessary to lift bulky packages which are particularly difficult to handle. One major difficulty in the handling of such items is providing an effective means for connecting the packages to hoisting or lifting devices. In many cases in the past, it has even been necessary to manually tie a line around the package and hook the line to a suitable hoist. This process was not only time-consuming, but also hazardous in that the line could possibly break, therein allowing the package to fall, causing injury to the article as well as to present a possible hazard to persons nearby.

One principal object of the invention is to provide a self-actuating latching mechanism for two flexible linkages which is caused to latch onto the linkages when the linkages are moved to a predetermined position within the mechanism.

Another object of the invention is to provide a guide and latching mechanism for two flexible linkages interconnected at a predetermined point by a pin in which the pin is arranged to act against a cam of the mechanism to cause the cam face to lock the pin within the mechanism when the pin is drawn into the mechanism by the linkages.

A further object of this invention is to provide a release mechanism for forcing package-supporting members of a hoist to pivot out of engagement with a supported package.

Still another object of the invention is to provide a latching mechanism for a lifting structure which enables weight transfer from the body of the structure to movable load-engaging members of said structure and vice versa.

Yet still another object of the invention is to provide an interconnecting mechanism between a hoist and hard to handle packages, with a latch mechanism having a simple, manually operated release to effectuate an easy release of the packages upon actuation.

And yet still another object of the invention is to provide tong-like members pivotally mounted to a support beam with the members arranged to engage with a plurality of bale-like packages in such a way that the load weight forces the members into tighter load engagement upon lifting of said structure.

And yet still another object of the invention is to provide a bale lift with two article engaging members which may be set upon an object or objects to form a connection therewith. A flexible linkage connects the members through a linkage guide and latch assembly to a lifting mechanism. The guide and latch mechanism is arranged to clutch into the flexible linkage in order that

2

the members will remain in engagement with the article or articles to be lifted through a lifting operation. The latching and guide mechanism is also provided with a trigger release which disengages the latching relationship between the latching and guiding mechanism and the flexible linkage, therein causing load weight via the linkage to move the members from engagement with the object or objects being handled.

Other objects of the present invention will become apparent upon reading the following specification and referring to the accompanying drawings in which similar characters of reference represent corresponding parts in each of the several views.

In the drawings:

15 Figure 1 is an elevational view of the lifting device shown with the article engaging members piercing two adjacent bales.

Figure 2 is a similar view of Fig. 1 with the article engaging members in a load releasing condition.

20 Figure 3 is an enlarged top plan view of the latching mechanism of the invention.

Figure 4 is an enlarged sectional elevational view taken at line 4—4 of Fig. 3 shown in a load locking condition.

25 Figure 5 is a view of the structure of Fig. 4 in the load releasing condition.

30 Referring now to the drawings, there is provided a mechanism which may be attached to a convenient hoist in order that the hoist may be readily connected and disconnected from bulky packages, such as, for example, bales of hay, cotton, or waste materials. A beam or block A is provided at both ends with a tong-like hook assembly B, each of which is pivotally mounted to the frame so that when the frame is laid upon two adjoining bales C, the hook assembly may be rotated to pierce the 35 bales.

35 Flexible linkages, such as chains D, are attached to a hoist hook E and interconnected with hook assemblies B, after passing through a chain, guide and latching mechanism F. Beam or frame A is made of a hollow aluminum channel to reduce weight.

40 A pivot pin 12 is provided on either end of the beam which rotatably mounts hook assemblies B thereto by an arm 13. Arcuate blades 14 are provided at the end of the arms 13 and the lower section of each has a sharply 45 pointed end 15, while the upper portion is provided with an eye 16. Hook assemblies B are operated by handle 17 extending outwardly from blades 14 and upwardly from arms 13. Each blade 14 is arranged in such an arc that the entire length of the center line of the blade is an equal distance from pivot pin 12.

45 Chains D attached to eye 16 via a ring 18 pass to chain guide and latching mechanism F and therefrom upwardly to a ring 19 joining the chains and engaged with hook E. The upper portions of the chains are interconnected by a pin 32.

50 Mechanism F is an important feature of the invention which enables the chains to be latched to mechanism F when the chains are pulled through the mechanism beyond a predetermined point, such as by pulling blades 14 downwardly. A cam 25 is arranged to coact with pin 32 between chains D and thereby to rotate to a position wherein the cam is locked in position with the pin held within the mechanism by notches in the cam face. Cam 55 25 is provided with a notch comprising a face 33 and a face 42. The point of intersection of face 42 and the periphery of the cam is designated as 34. The cam is notched at 37 at a point approximately diametrically opposite the pin receiving notch.

55 Cam 25 is rotatably mounted on a pin 26 supported by 60 brackets 30 integral to the mechanism so that chains D enter the body of assembly F at openings 27 and 28 and pass upwardly on either side of cam 25. The cam is 65 arranged to clutch into the flexible linkage in order that

allowed to rotate within throat 35 of mechanism F in cuts 29 and 31 which are of sufficient size to allow the cam free movement except where the cam face at point 34 is arranged to make contact with throat 35 above cut 31. This arrangement prevents counter clockwise rotation of the cam beyond a predetermined point.

When chains D are drawn through mechanism F, pin 32 engages with face 33 to force the cam to rotate in a counter clockwise direction. However, when the pin is drawn to a predetermined point within mechanism F, point 34 of the cam makes contact with throat 35 thereby preventing further rotation of the cam and holds face 33 in a condition wherein pin 32 is unable to pass further into the body of the mechanism.

A trigger lever 38 is pivotally mounted to frame A by a pivot pin 39. Trigger lever 38 is urged against cam 25 by a spring 41. When cam 25 rotates in a counter clockwise direction, as by pin 32 being drawn into the throat of mechanism F, trigger lever 38 is forced inwardly by spring 41 to engage with notch 37, therein locking the cam against clockwise rotation. When mechanism F is in this condition, cam face 42 is in a position wherein pin 32 is unable to retract from mechanism F.

Operation

When pin 32 is pulled downwardly into mechanism F, as by spreading assemblies B, the pin asserts force against cam face 33, causing the cam to rotate in a counter clockwise direction until trigger lever 38 falls into engagement with notch 37. In this condition cam face 42 prevents upward movement of pin 32 and face 33 prevents the pin's downward movement. A chain 45 is attached to lever 38 and is provided on the end with a ring 46 which may be pulled to disengage lever 38 from notch 37 therein freeing cam wheel 25 for rotation in a clockwise direction wherein pin 32 is enabled to act against face 42 and retract from throat 35.

When two bales C are laid end to end, block A may be placed centrally over the junction of the two blades. Blades 14 are then rotated about pivot point 12 by applying manual pressure to handle 17 so that the pointed ends 15 pierce the blade. As blades 14 are rotated into the bale, chains D pull pin 32 into latching mechanism F. Thus chains D pull eyes 16 of hook assemblies B inwardly to release the hook assemblies from the bales.

In this mechanism hook assemblies have been illustrated as having blades 14. However, it is clear that other article-engaging members can be equally well employed.

Although the foregoing invention has been described in some detail by way of illustration and example for purposes of clarity of understanding, it is understood that certain changes and modifications may be practiced within the spirit of the invention and scope of the appended claims.

What is claimed is:

1. A latching assembly for a pair of flexible linkages comprising a linkage guide body, said linkages disposed to move within said body, a cam mounted in said body between said linkages, a stop member connecting said linkages, a notch in said cam, said stop member and notch arranged to move said cam upon movement of said linkages in one direction to a locked position, means to lock said cam in said locked position, said cam arranged to co-act with said guide body to prevent movement of said linkages through said body when said cam is in locked position, and manually operable means to disengage said cam locking means whereby said cam is free to move from said locked position.

2. A locking mechanism for a pair of flexible linkages comprising a linkage guide assembly, a cam supported by said assembly to rotate between said linkages, a pin connecting said linkages, said pin disposed to engage with said cam when said linkages are pulled down through said assembly, said cam having a notch comprising a first and a second pin engaging face, stop means to stop counter

clockwise cam rotation at a position with said first face of said cam adjacent the inside wall of said guide assembly to prevent passage of said pin through said assembly, a cam locking lever pivotally mounted adjacent said assembly, a lever engaging face on said cam to engage said lever and lock said cam against clockwise rotation, spring means to bias said lever against said cam, said pin disposed to act against said first face of said cam and move said lever engaging face into locking engagement with said lever when said linkage is pulled down through said assembly, said second face disposed with one end of the second face adjacent the wall of said guide assembly to hold said pin within said guide against upward movement past said second face when said lever engaging face and said lever are in a locked condition, and means to disengage said lever from said lever engaging face of said cam whereby said cam is freed to release said pin.

3. An article lifting mechanism comprising a frame, article engaging members carried pivotally by said frame, a flexible linkage for each said member, a guide for said linkages disposed centrally on said frame between said members, a cam rotatably mounted on said guide between said linkages, connecting means connecting said linkages, said connecting means arranged to rotate said cam in a first direction when said members are moved to a first position, cam locking means actuated by said cam when said cam is rotated a pre-determined distance in said first direction, means comprising said cam to lock said connecting means within said guide while said cam is in said locked position, and means to release said locking means whereby said cam is freed to release said pins means.

4. An article lifting mechanism comprising a frame, article engaging members carried pivotally by said frame, flexible linkages connected to said members, a guide for said linkages disposed centrally on said frame between members, a cam engaging means connecting said linkages, a cam mounted on said guide to rotate between said linkages, said cam having a first notch with a first and a second face disposed to be engaged by said cam engaging means, a cam locking lever pivotally mounted to said frame, a spring normally biasing said lever against said cam, a second notch on said cam disposed to engage said lever to lock said cam against rotation in a pre-determined direction, said cam engaging means arranged to act against said first face of said cam to rotate said cam to a position where said lever engages means on said guide to limit movement of said cam beyond a pre-determined degree of rotation and position said first face sufficiently close to the wall of said guide to lock said cam engaging means against downward movement through said guide, said second face of said cam disposed sufficiently close to the inside wall of said guide to lock said cam engaging means within said guide against upward movement when said second notch of said cam and said lever are in locked condition, and means to disengage said lever from said second notch of said cam whereby said cam is freed to release said pin.

5. An article lifting mechanism comprising a rigid support beam, arcuate blades pivotally mounted from ends of said beam, a handle for each said blade to force said blades into article piercing position, flexible linkages connected to free ends of said blades, a guide for each said linkage disposed centrally on said beam between said blades, a cam engaging pin connecting said linkages, a cam rotatably mounted on said guide between said linkages and disposed to engage with said pin, a cam locking lever pivotally mounted on said beam, spring means normally biasing said lever against said cam, a lever engaging notch on said cam disposed to engage said lever to lock said cam against rotation in a predetermined direction, said cam having a second notch with a first and a second pin engaging face, said pin arranged to act against said first face of said cam to move said cam to a position where said lever engages with said lever engaging notch

of said cam, means to stop rotation of said cam beyond a predetermined point and position said first face to stop said pin from downward movement through said guide, said second face of said cam disposed to lock said pin within said guide against upward movement when said lever engaging notch and said lever are in a locked position, and means to disengage said lever from said lever engaging face of said cam whereby said cam is freed to release said pin.

6. An article lifting mechanism comprising a rigid support beam; arcuate blades having an article piercing end and a free end, said blades pivotally mounted from opposite ends of said beam, means for rotating said blades downwardly into article piercing engagement, a pair of flexible linkages, each linkage connected to the free end of one said blade, a guide for said linkages dis-

posed centrally on said beam between the said blades, said linkages arranged to be drawn down through said guide when said blades are moved into article piercing engagement, a cam carried by said guide to rotate between said linkages, connecting means connecting said linkages, said connecting means arranged to rotate said cam in a predetermined direction when said linkages are drawn downwardly through said guide, cam locking means actuated by said cam when said cam is moved a predetermined distance in said predetermined direction, means comprising said cam to lock said connecting means within said guide while said cam is in locked position, and manually actuated means to release said locking means whereby said cam is freed to release said pin.
